MECHANICAL TIME FUSE

Helmut Junghans, Schramberg-Sulgen, Germany

Application July 24, 1937, Serial No. 155,445
In Germany May 17, 1935

3 Claims. (Cl. 102—36)

This invention relates to a mechanical time fuse which is sensitive to impact, and of which its mechanism is substantially identical to that described in my Patent No. 2,011,286. The characteristic features of the invention disclosed there-in were a device for delayed action containing a clockwork mechanism with balance disposed centrally in the fuse, and with a sensitive impact device having a common locking element which is capable of being released singly by either method of ignition.

The locking element is constructed in the form of a shaft having an arm which is adapted to enter a corresponding slot in the time disc and to release the firing element by reason of the rotating disk. The shaft is also mounted in a special bearing which can be displaced by the downwardly moving percussion pin, in such fashion that the firing element is released from the locking member. In order to maintain the movable bearing in the position of rest there is employed a spring-controlled member which is actuated by the downwardly moving percussion pin. The bearing is thus able to move under the action of the centrifugal force for a release of the firing element.

The purpose of my invention is to provide a time fuse substantially identical to that described in my Patent No. 2,011,286 but wherein the impact device is of increased sensitivity. To accomplish this object the invention provides means for making the resiliency of the notch lever, which is actuated by the percussion pin upon the downward movement, of a more elastic nature. This enhanced resiliency is made up in part of the natural resiliency of the said lever and in part of the adjustable spring force of a spring-pressed bolt engaging with the notch lever.

By means of this arrangement it is possible to not alone increase the resiliency of the notch lever, but to also make it readily adjustable. It is impossible to reduce the spring force of the notch lever below a certain amount for the reason that as the effect of the centrifugal force on the resilient notch lever would impair the action of the lever and render the same less reliable. To preclude this effect of the centrifugal force it might appear natural to reinforce the resilient portion of the notch lever. This method, however, is unsuitable owing to the fact that in this way the resiliency would become hard and delay the action. It is only by the co-operation of two elastic agents that the force maintaining the notch connection can be increased whilst upholding or increasing the elasticity of the device.

An embodiment of the invention is illustrated by way of example in the accompanying drawing, in which

Fig. 1 is a plan view of a fuse plate with the hook arrangement and the spring-pressed bolt 5 engaging with the hook, in the locked position.

Fig. 2 is a cross-section of the embodiment shown to Fig. 1, there also being shown parts of the operating and releasing mechanism.

Figs. 3 and 4 show the hook arrangement corresponding to Figs. 1 and 2 in the position of release.

To facilitate an understanding of my present invention I will give a short description of the principal structural features of the time fuse 15 according to my Patent No. 2,011,286.

The central shaft 19 of the clockwork, on which is mounted the adjustment disc 20, is bored throughout its entire length. In this bore is guided the percussion bolt 11 which, upon impact 20 of the projectile against any resistance, is pressed down. In order that this movement may not take place at the firing, a safety tube lying above the mechanism, but not shown, is provided for the percussion bolt 11.

When the fuse is set for retarded ignition, the engaging lever 21 securely connected with the shaft 5 slides in the known manner with its bent-up end (not shown) on the circumference of the adjustment disc 20 driven by the mechanism, 30 until the bent up end falls into the aperture 20a of this disc, whereby the shaft 5 is subjected to a slight rotation, owing to which a lever 18 is able to enter the milled out recess 5a of the shaft 5, which brings about the engagement of the ignition device of any desired form, which is not shown.

An immediate release of the lever 18 takes place upon the impact owing to the fact that the shaft 5 is shifted outwardly instead of being rotated, 40 in that its bearings, or only one of them, are enabled to shift outwardly by centrifugal force.

For this purpose in the plate 1 there is provided a recess 1 acting as guide for the radially shiftable bearing bridge 3. The bearing bridge 3 possesses at its outer end a bore 4 for accommodation of the locking member 5, which is constructed in the form of a shaft or bolt. At the inner end the bridge 3 possesses an upwardly directed projection 6 engaging with a spring hook 50 8 which is screwed firmly to the plate at 9. On the front end of the hook there is fitted a conical member 10 which by means of its inclined surface co-operates with the percussion pin 11 having the corresponding conical point, in such fash- 55

ion that the percussion pin when moving downwards is able to move the hook to one side and thus release the connection. Despite the approximately central position of the resilient portion of the hook this part is acted upon to a slight extent by centrifugal force. In order now to increase the spring effect and also the elasticity of the device there is provided a spring-pressed bolt 12 accommodated in a corresponding 10 boring 13 in the upper plate 14 and acted upon by the spring 15, for the setting of which there is provided the screw 16 closing the boring at the end. The spring-pressed bolt 12 engages with the upwardly bent lug 17 of the hook 8 and 15 opposes the opening of the hook connection.

By reason of the centrifugal force the action of the pressure bolt is again in part overcome. The force of the pressure spring should, therefore, be selected accordingly. It will be obvious 20 that the safety means as described also offers advantage when the fuse is subjected to jolts or the like during transport, as it will oppose any undesired opening of the hook connection.

The operation of the fuse is as follows:—

25 In case of time ignition the arm on the shaft or bolt 5 enters a slot in the time disc in the known fashion. Owing to the rotation of the shaft or bolt thus caused the firing element 18 is released. In case of impact ignition the hook 30 connection with the bridge 3 is released by the percussion pin and the bridge 3 is moved outwardly whereby, the shaft or bolt 5 is caused to assume an inclined position, so that also in this case the firing element 18 is released.

35 Having now particularly described and ascertained the nature of my said invention, and in

what manner the same is to be performed, I declare that what I claim is:—

1. In a mechanical time fuse the combination with firing control means, of a shiftable element 5 controlling said means, a resilient lock lever adapted for locking and releasing said shiftable element, a movable bolt engaging said lock lever, a spring behind said bolt for causing a pressure on said lever, means for adjusting the pressure of said spring and a percussion pin for releasing 10 said lock lever against the combined resilient forces of said lever and spring.

2. In a mechanical time fuse the combination with firing control means, of a shiftable element 15 controlling said means, a resilient lock lever of substantially soft resiliency adapted for locking and releasing said shiftable element, a lug extending from said lever, a movable bolt engaging said lug, a spring behind said bolt for causing a 20 pressure on said lever, means for adjusting the pressure of said spring and a percussion pin for releasing said lock lever against the combined resilient forces of said lever and spring.

3. In a rotated mechanical time fuse the combination with firing control means of a resilient lock lever for controlling said means, a 25 spring element operatively engaging said lock lever and a percussion pin for releasing said lock lever against the combined resilient forces 30 of said lever and spring, the sum of the resilient forces of both said spring element and said lock lever being greater than the centrifugal force acting on said lever due to the rotation of said fuse.

HELMUT JUNGHANS. 35
